HAIR WAVING CLAMP

Otto Seiter, Forest Hills West, N. Y., assignor to
 The Nestle-Lemur Company, New York, N. Y.,
 a corporation of Ohio

Application December 2, 1935, Serial No. 52,520

13 Claims. (Cl. 132—33)

This invention relates to improvements in the art of waving human hair and has particular reference to holding devices for a wound strand of hair.

5 In the prior Patent No. 1,919,282, issued July 25, 1933, there is disclosed a holding device for a strand of hair including a clamp and a curling rod in which the clamp is utilized to grip a strand of hair close to the scalp and to receive the 10 curler rod upon which the strand is wound.

In this holding device, the hair was adapted to be treated by a moistened pad and a heater to cause a permanent waving effect.

The clamp included a pair of pivotally connected elongated members brought securely together by a latching device to hold the hair strand therebetween.

The clamp, in the form shown, was provided with spaced pivot mounts for the curler rod and cooperating ratchet means to enable the curler 20 rod to be wound up under tension.

The cooperating ratchet means, as disclosed in said patent, consisted of a ratchet formed on one end of the curler rod and a pawl carried by the clamp which is engageable with the ratchet so as to prevent rotation of the rod in a direction which would relieve the tension on the hair strand and allow it to become loosened on said rod.

30 The present invention is particularly directed to a holding device of the character mentioned above in which the base of the clamp is formed of a molded piece of bakelite or other plastic material while the other pivotally connected 35 clamping member consists of a rubber covered metal arm and it is among the objects of the present invention to simplify the construction of the base and to enhance its strength without substantially increasing its weight or expense 40 of manufacture and it is a further object of the present invention to provide a rubber covered metal arm member which will automatically adjust itself to different thicknesses in the hair which is being held between said pivotally connected members.

45 It is still a further object of the present invention to provide a clamping construction in which the hair may be treated closely adjacent to the roots thereof without there being a substantial portion extending through the clamp and between the clamping members and the rod not subject to the proper treatment.

50 Other objects will be obvious or will appear during the course of the following specifications.

55 In one preferred embodiment accomplishing

the above mentioned objects, the base clamping member is formed of a relatively thin rectangular piece or plate of a molded plastic material, such as bakelite, which is peripherally slotted or grooved to receive a metallic reinforcing rib 5 at one side face, the ratchet connection and one pivot mount at one end face, the latching member at its other end face and the clamping rod at the other side face, which clamping rod is pivotally connected to the ratchet structure. 10

The clamping rod itself preferably consists of a channel sheet metal strip receiving a sinuous spring member which channel strip is enclosed by another channel strip, the spring member tending to bias the two enclosing or enveloping 15 strips apart.

Over the two channel strips is placed a rubber tube which rubber tube is adapted to be pressed into the groove or hollow in the side of the clamping bar by the latch arrangement above 20 described.

The mounts for the curling rod at the ends of the clamp are preferably so positioned that the center of the curling rod will be held directly over the front edge of the clamping bar with 25 the result that there will be a minimum extent of hair between the clamping jaws and the curling rod not subject to the heat and moisture treatment.

The inventive idea involved is capable of receiving a variety of mechanical expressions, one of which, for purposes of illustration is shown in the accompanying drawings, wherein:—

Figure 1 is a perspective view of the clamp 35 curler rod and heater in position thereon with a portion of the heater removed to show more clearly the clamp.

Figure 2 is a side elevation on the line 2—2 of Figure 1, showing the combined heater curling rod and clamp.

Figure 3 is a top view upon the line 3—3 of Figure 2 in fragmentary section and upon enlarged scale.

Figure 4 is a fragmentary side elevational view on the line 4—4 of Figure 3 showing the detachable pivot connection between the clamping rod and clamping bar.

Figure 5 is a bottom view upon the line 5—5 of Figure 4 of said detachable pivot connections.

Figure 6 is a transverse sectional view upon 50 the line 6—6 of Figure 3.

Figure 7 is a perspective view illustrating how the strand of hair may be wound upon the curler before the curler is placed in position as indicated in Figures 1 and 2.

Figure 8 is an exploded perspective view showing the various elements of the clamp upon enlarged scale.

Figure 9 is an additional exploded view of the 5 clamping arm.

Referring to Figures 1 to 9, there is shown a heater A, a curling rod B and a clamp C.

The clamp C to which this invention is particularly directed is provided with two clamping 10 members, one clamping member D consisting of a base molded or formed out of an insulating material, such as bakelite, hard rubber or some other plastic, and the other E of an arm pivotally connected adapted to be clamped against 15 said base D by the latch F.

The base D also carries one pivotal mount G and the latch F carries the other pivotal mount H for the curling rod B.

The base D consists of an oblong rectangular 20 shaped base of bakelite, hard rubber or other plastic material, the opposite long edges of which are provided with longitudinal recesses 10, 11 and the short lateral sides of which are provided with recesses 12, 13.

25 The bakelite or plastic base D is preferably of relatively small dimension, for example, $\frac{5}{8}$ of an inch in width, $2\frac{3}{4}$ inches in length and $\frac{1}{16}$ of an inch in thickness, in order to assure inexpensiveness and light weight in construction.

30 The base D is most desirably reinforced by placing in the slot 10 the closely fitting metal strip or plate 14 which is riveted in position by the drive screws 15. (See Figures 3 and 8).

35 The strip or plate 14 terminates at 16 without extending into the slot 13, but is provided with a forward extending flange 17 at its other end which fits into the side slot 12 and projects beyond the base D to form the holed ear 18, said ear serving as a pivot mount for the swinging 40 clamping arm E.

The end of the plate 14 is provided with the upturned flange portion 19 which covers the end of the base D above the slot 12.

The upturned portion 19 has the extension 20, 45 a portion of which is bent sidewardly as indicated at 21 to form a finger piece and the forward portion of which has an outwardly projecting finger 22 forming the semi circular recess 23. This recess 23 receives the full diameter 50 end portion 24 of the curler rod B adjacent the ratchet 25. The end portion 24 also receives 55 the pivotal connection 26 of the finger 27 which is adapted to cooperate with the concave and roughened center portion 28 of the curling rod B (see Figures 1 and 7).

The slot 12 and the adjacent end of the slot 10 are made of increased depth to receive the extra plate 29 which may be riveted or spot welded, as indicated at 30, to the terminal portion 60 of the reinforcing plate 14.

The plate 29 is provided with an extension 31 which extends forwardly and then is upturned, as indicated at 32, to form the finger piece 33 at the upper end of portion of which piece 33 is cut inwardly to form a pawl 34 (see Figures 3 and 8).

70 The pawl 34 is adapted to engage the teeth of the ratchet 25 and it has sufficient resiliency normally to firmly engage with said ratchet teeth 25.

The end of the curling rod 27 is squared, as indicated at 35, and is adapted to receive a key (not shown) to enable the ratchet 25 to be 75 turned up in the direction indicated by the ar-

row 36 on Figure 1 to tighten the hair upon the curler rod B.

At the same time, the finger piece 33 has sufficient resiliency so that by placing the index finger upon the finger piece 21 and the thumb upon the finger piece 33, the pawl 34 may be released in turn releasing the curling rod 28, and then the curling rod 28 lifted out of position.

The ratchet 25 and the curling rod 28 may be readily placed in position by pressing the pivotal portion 24 thereof into the recess 23, the resiliency of the spring finger 33 permitting the pawl 34 to slip into position on the ratchet teeth 25 (see Figure 1).

It will be noted that the base structure D is somewhat extended below the slot 12 as indicated at 37 to support the flange 31 which carries the pawl finger piece 32.

It will be noted that the semi-circular recess 23 is centered over the front edge of the bar B so as to reduce to a minimum the length of the strand of hair clamped between the bar B and the arm E and coiled on the curling rod 28.

The ear 18 is enclosed between the bored jaws 38 extending from channel frame member 40. The pin 41 extends through the coinciding holes or openings in the jaws 38 and ear 18 and serves as the pivot mount of the swinging arm E.

The pin 41 is carried on the resilient leaf 42 which is pivotally connected at 43 to the outside channel member 45 which closely fits over and encloses the open side of the channel member 40.

Enclosed in the channel member 40 is the sinuous spring 46 which is held in position by the pin 47 (see Figure 9). The rear portions 48 of said sinuous spring abut against the back edge 49 of the channel member 40 and the front portions 50 abutting against the front edge 51 of the outside or enclosing channel member 45.

It will be noted that the channel member 40 is recessed at 52 between the shoulders 53 and that the outer channel member 45 fitted over this recessed portion, the two channel structures 40 and 45 being biased apart by said spring 46, that the outside channel structure 45 being loosely mounted on the inside channel structure 40 so that a swinging movement between said channel structures may readily take place.

The two channel structures are held together and are enclosed within the rubber tube 54, the 50 embossments or knobs 55 stamped on the edge 56 of the U-shaped structure 45 assuring that such rubber tube will have an enhanced gripping face in respect to the hair when it is forced into the recess 11 of the base D.

The recess 11 of the bar D is provided with a series of steps 56 which terminate in the end groove 57 at the base of said recess, said steps 56 and bottom groove 57 extending the length of the bar D.

To the jaw members 60 at the other end of the inner channel member 40 is pivotally connected the ear 58 of the latch F by the pin 59. The ear 58 is positioned on the end of the plate member 61 which fits into the slot 13 at the end of the base D.

The element 61 carries the pivot mount H on an upturned vertical end flange 62. The flange 62 is provided with an upstanding portion 63 having the semi-circular recess 64 which receives 70 the bearing stud 65 at the other end of the curling rod (see Figure 1) extending away from the large diameter portion 66 which is held inside of the upstanding portion 63.

The other end of the bar 61 is provided with an 75

ear 67 fitted between the jaws 68 at the end of the finger member 71. The jaws 68 of said clamping bar F have vertical flange portions 69 to fit into the recess 70 at the corner of the bar D, the end of the metal insert plate 14 being correspondingly recessed as indicated at 70' in Figure 8.

It will be noted that the flanges 69 and the recess 70 are eccentric so that when the lever 71 is clamped against the face of the bar D, as indicated in Figure 3, the rubber sheath 54 will be clamped into the recess 11 and tightly hold the hair therein.

In operation, the end of the tress of hair to be subjected to the Croquignole or other permanent waving operation may be placed under the finger 27 after the tress of hair has been selected and clamped between the swinging arm E and the base plate D.

20 The rod B is turned until the hair has been all wound thereon and then the curling rod B with the hair thereon is placed in position in the recesses 23 and 64.

As the curling rod B is placed in position, the pawl 34 will snap on to the ratchet 25 and then by the application of the key to the squared nut 35 of the curling rod the hair may be tightened up.

Then, a pad may be placed over the hair on the curling rod B and then the heater indicated by A may be placed in position thereon and permitted to remain there for a desired length of time to cause the liquids on the pad to penetrate into and cause a thorough treatment of 35 the hair with steaming.

The pad may consist of a piece of flannel or felt impregnated with a suitable liquid and preferably backed by a sheet of metal foil and an impermeable paper cover, the felt or flannel being placed on the inside against the hair on the curling rod B and the foil and paper being placed on the outside and the paper contacting with the heater A.

The heater A consists of two partial cylindrical magnesium alloy (containing small amounts of aluminum and manganese) jaw members 85 which are outwardly bowed in their central portions to accommodate the shape of the hair. To the cylindrical elements 85 are connected the sheet metal arms 88 by the disks 86 and the rivets 87.

These sheet metal arms 88 are provided with inturned ears 89 through which passes the pivot rod 90, the upper portions of the arm structure 88 being also connected at 91 to the bakelite handles of the finger pieces 92. The spring 93 fits around the pivot rod and maintains the finger pieces 92 and 93 apart, the jaws 85 together.

The construction and operation of the heater 60 device A and the manner and means for preheating it and controlling its operation are not disclosed in the present application but forms the subject matter of co-pending applications, Serial Nos. 62,094; 62,095; 69,641 filed February 3, 1936, 65 February 3, 1936, and March 19, 1936, respectively.

It is thus apparent that the present application has provided a clamping device of light weight, and the base D of which may be readily manufactured from or molded out of bakelite 70 by readily available machinery with a minimum of cost.

By slotting the sides of the base D, as shown and inserting the strips 14, 17, 29, and 61, the base piece of bakelite is reinforced. In addition, the pivot mounts G and H, ratchet 32-21,

clamping arm E and latch F may all be inexpensively constructed from sheet metal and then subsequently assembled together and to cooperate with the base in a simple and convenient manner.

When so assembled on the base, the parts will not get out of order and will be extremely durable being capable of standing up over a long period of time although subjected to severe handling.

The resilient insertion 46 between the two channel shaped bar members 40 and 45 which enclose each other enables adjustment of this arm E to accommodate the different thicknesses or distribution of the hair upon the curling rod 15 B or passing between the clamping base D or clamping arm E and the clamping action will be more uniform for the entire length of the clamp.

In addition, the location of the pivot mounts 20 23 and 64 for the curler rod B directly over the front of the base D or the arm E of the clamp will lessen the extent of hair between that wound on the curler rod B and that clamped in position, so that a maximum length of the hair will be 25 treated by the heater A and by the moisture of the treating pad.

It is apparent that the specific illustrations shown above have been given by way of illustration and not by way of limitation and that 30 the structures above described are subject to wide variation and modification without departing from the scope of intent of the invention, all of which variations and modifications are to be included within the scope of the present invention.

What is claimed is:

1. A hair waving clamp, particularly adapted for Croquignole waving, comprising a base, a clamping arm pivotally mounted thereon, bearing 40 means for a curling rod mounted on said base, a detent for a curling rod mounted on said base and a latch connected to said arm for locking said arm against said base, said base being molded of bakelite or a similar plastic, and being slotted 45 on its face opposite said arm to receive a metallic reinforcing rib.

2. A hair waving clamp, particularly adapted for Croquignole waving, comprising a base, a clamping arm pivotally mounted thereon, bearing 50 means for a curling rod mounted on said base, a detent for a curling rod mounted on said base and a latch connected to said arm for locking said arm against said base, said base being molded of bakelite or a similar plastic, and being 55 slotted at all four edges to receive supports for said bearings and detent.

3. A hair waving clamp, particularly adapted for Croquignole waving, comprising a base, a clamping arm pivotally mounted thereon, bearing 60 means for a curling rod mounted on said base, a detent for a curling rod mounted on said base and a latch connected to said arm for locking said arm against said base, said bearing means and detent being mounted on metallic 65 strips and said base being provided with slots to receive said strips.

4. A hair waving clamp, particularly adapted for Croquignole waving, comprising a base, a clamping arm pivotally mounted thereon, bearing 70 means for a curling rod mounted on said base, a detent for a curling rod mounted on said base and a latch connected to said arm for locking said arm against said base, said base being molded of bakelite or a similar plastic, and said base 75

being provided with slots along the two sides and rear face thereof, the rear slot receiving a metallic reinforcing strip and said latch and bearing means including additional strips fitted into said 5 side slots.

5. A hair waving clamp, particularly adapted for Croquignole waving, comprising a base, a clamping arm pivotally mounted thereon, bearing means for a curling rod mounted on said 10 base, a detent for a curling rod mounted on said base and a latch connected to said arm for locking said arm against said base, said pivot mount of said arm including cooperating bored enclosing and interfitting members respectively on the 15 pivotally connected elements a pin passing through the bores of said members and spring mount for said pin holding it in position.

6. A hair waving clamp, particularly adapted for Croquignole waving, comprising a base, a 20 clamping arm pivotally mounted thereon, bearing means for a curling rod mounted on said base, a detent for a curling rod mounted on said base and a latch connected to said arm for locking said arm against said base, said pivot mount of 25 said arm including cooperating bored enclosing and interfitting members respectively on the pivotally connected elements a pin passing through the bores of said members and spring mount for said pin holding it in position, said 30 spring mount including a spring leaf pivotally mounted on said arm enabling pivotal movement of said pin and also enabling said pin to be readily withdrawn from said bores by the operator.

35 7. A hair waving clamp particularly adapted for Croquignole waving, comprising a base, a clamping arm pivotally mounted thereon, bearing means for a curling rod mounted on said base, a detent for a curling rod mounted on said base and a latch connected to said arm for locking said arm against said base, said arm including two 40 channel members telescoped into and enclosing each other and a rubber tube fitting over and holding said channel members together.

45 8. A hair waving clamp particularly adapted for Croquignole waving, comprising a base, a clamping arm pivotally mounted thereon, bearing means for a curling rod mounted on said base, a detent for a curling rod mounted on said base and a latch connected to said arm for locking 50 said arm against said base, said arm including

two channel members telescoped into and enclosing each other and a rubber tube fitting over and holding said channel members together, said channel members being resiliently pressed apart against said rubber tube. 5

9. A hair waving clamp, particularly adapted for Croquignole waving, comprising a base, a clamping arm pivotally mounted thereon, bearing means for a curling rod mounted on said base, a detent for a curling rod mounted on said base 10 and a latch connected to said arm for locking said arm against said base, said arm including two intertelescoping and relatively sliding members, and an inter-spring to bias said members apart enclosed by said sliding members. 15

10. A hair waving clamp, particularly adapted for Croquignole waving, comprising a base, a clamping arm pivotally mounted thereon, said pivot mount of said arm including cooperating bored enclosing and interfitting members re- 20 spectively on the pivotally connected elements, a pin passing through the bores of said members and spring mount for said pin holding it in position.

11. A hair waving clamp particularly adapted for Croquignole waving, comprising a base, a clamping arm, and a pivotal connection between said arm and said base including a pivot pin, a spring leaf pivotally mounted on said arm enabling pivotal movement of said pin and also 30 enabling said pin to be readily withdrawn by the operator.

12. A hair waving clamp, particularly adapted for Croquignole waving, comprising a base, a 35 clamping arm pivotally mounted thereon, said arm including two channel members telescoped into and enclosing each other and a rubber tube fitting over and holding said channel members together.

13. In an apparatus for waving hair, a clamp 40 comprising opposed elements hingedly connected, means for securing the elements in closed position, one of the elements carrying a resilient jaw pivotally supported thereon and adapted to co- 45 operate with the other element to clamp the hair, said jaw consisting of two interfitting elongated members of U-cross section biased apart by an interiorly positioned resilient member and held together by an enclosing rubber tube. 50

OTTO SEITER.
